United States Patent Office

Des. 206,372
Patented Dec. 6, 1966

206,372

DRAWER HANDLE

Cornell D. Hazenberg, Jamestown, N.Y., assignor to Chautauqua Hardware Corporation, Jamestown, N.Y., a corporation of New York

Filed Jan. 25, 1966, Ser. No. 802

Term of patent 14 years

(Cl. D10—8)

FIG. 1

FIG. 2

FIG. 1 is a front view of a drawer handle showing my new design; and

FIG. 2 is an end view of the handle.

I claim:

The ornamental design for a drawer handle, as shown.
